Des. 241,745
Patented Oct. 5, 1976

241,745

HOOD FOR GUN SIGHTS

Verne J. Antonius, 720 Maryland St.,
El Segundo, Calif. 90245

Filed Nov. 19, 1975, Ser. No. 633,464

Term of patent 14 years

Int. Cl. D22—05

U.S. Cl. D22—7

FIG. 1

FIG. 7

FIG. 2

FIG. 3

FIG. 4

FIG. 5

FIG. 6

FIG. 1 is an isometric view of a new hood for gun sights;

FIG. 2 is a side view thereof;

FIG. 3 is a top view thereof;

FIG. 4 is a view of the opposite side thereof;

FIG. 5 is a bottom view thereof; and

FIGS. 6 and 7 are end views of the forward end and the rearward end, thereof, respectively.

I claim:

The ornamental design for a hood for gun sights, as shown.
